His Attorney.

UNITED STATES PATENT OFFICE

2,002,381

ELECTRIC DISCHARGE DEVICE

Willem F. Westendorp, Schenectady, N. Y., assignor to General Electric Company, a corporation of New York

Application July 21, 1934, Serial No. 736,363

4 Claims. (Cl. 176—124)

My invention relates to electric discharge devices and more particularly to circuits and apparatus for operating the same.

One object of my invention is to provide a simplified apparatus for operating a thermionic type of discharge lamp on a series lighting circuit.

Another object of my invention is to provide a single transformer for supplying both the discharge current and the cathode heating current for the lamp.

Another object of my invention is to provide an improved circuit for operating the hot cathode type of electric discharge devices wherein a preheating of the cathode is required.

For a better understanding of my invention, together with other and further objects thereof, reference is had to the following description, taken in connection with the accompanying drawing, and its scope will be pointed out in the appended claims.

In the accompanying drawing, Fig. 1 illustrates diagrammatically an electric discharge lamp of the hot cathode type connected in accordance with my invention to a single transformer which supplies both the discharge current and the cathode heating current; Fig. 2 illustrates diagrammatically a hot cathode discharge lamp connected to a direct current series circuit and arranged, in accordance with my invention, for automatic preheating of the cathode before each starting of the lamp.

Referring to Fig. 1 in detail, the primary winding 1 of the transformer 2 is connected into a constant current circuit. The transformer 2 is provided with a single core 3 and secondary windings 4, 5 and 6. The secondary windings are connected to an electric discharge lamp 7 which is provided with a pair of anodes 8 and 9, a pair of cathodes 10 and 11 comprising metal filaments and a glass envelope 12. The anode 8 is connected to cathode 10 and the anode 9 is connected to cathode 11 so that when, during operation, alternating current is provided, each of the structures operates alternately as an anode and as a cathode. The winding 4 is connected to the ends of cathode 10 by the conductors 13 and 14 and the winding 6 is connected to cathode 11 by the conductors 15 and 16. The conductors 14 and 15 are also connected respectively to the winding 5 and to the ends of the cathodes 10 and 11 which are remote from the anodes 8 and 9, so that the current circulating through winding 5 must necessarily flow through the two cath-

odes and the discharge path between the anodes 8 and 9 in series.

The primary winding 1 of the transformer 2 being connected in a constant current circuit produces a substantially constant average flux for exciting the windings 4, 5 and 6. It is, therefore, necessary to maintain the load on these three windings substantially constant to prevent an undue unbalancing of the available energy which would occur if one section were open circuited. Such condition would overload the closed circuited section of the winding and raise beyond safe limits the voltage across the terminals of the open-circuited section.

In the arrangement in accordance with my invention, I provide a time delay thermostatic switch 17 for opening and closing a shunt circuit about the discharge path in the lamp, this circuit being arranged to carry full load current when closed. The switch 17 is provided with a pair of contacts 18 and 19, a thermostatic member 20 for moving the contact 18 into and out of engagement with contact 19 and a heater 21 for causing the member 20 to operate. The contact 19 is connected in series with a loading resistor 22 to conductor 14 and the contact 18 is connected through the element 20 and conductor 23 to the conductor 15. The heater 21 is connected across the conductors 15 and 16 by the conductors 23 and 24.

When current begins to flow through the winding 1, the contacts 18 and 19 are in engagement and a current equal to normal load current flows through the resistor 22. The windings 4 and 6 are also excited and being permanently connected to the cathodes 10 and 11 heat them. The heater 21 in the meantime is also energized by the winding 6. The heating of this element is so arranged that a predetermined time period elapses before it deflects and thereby opens the circuit. The cathodes are thereby given time to rise to the proper temperature before starting potential is applied across the lamp. When the thermostatic switch operates, the contacts 18, 19 open and the potential of winding 5 is applied to the lamp. If the discharge does not start instantaneously the temperature of the filaments is automatically increased and the potential of the winding 5 also is increased so that the present arrangement provides the additional voltage necessary for starting the lamp.

The above circuit provides in effect a shunt operation of the cathodes and the discharge path, because there is a division of the available energy between the transformer winding sections. I

have provided an equivalent circuit for operating a lamp with direct current as is shown in Fig. 2. Fig. 2 illustrates an electric discharge lamp 25 provided with an anode 26, a cathode 27 and a cathode heater 28. The heater 28 is preferably a metal filament connected at one end to the cathode and at the other end to the anode terminal by a conductor 29. The heater is, therefore, connected in parallel to the discharge path between the anode 26 and cathode 27. A second conductive path, connected in shunt to the discharge path, includes a switch 30 and a resistor 31. The switch 30 comprises a thermostatic element 32 provided with a contact 33 which it moves into and out of engagement with contact 34 in response to the operation of a heater 35. When the contacts are in engagement, a circuit is closed which may be traced from the cathode terminal through resistor 31, conductor 36, contacts 34, 33, element 32, conductor 37 to the anode terminal.

The anode and cathode terminals are respectively connected into a series circuit indicated by conductors 38 and 39 to which substantially constant current is supplied. The heater 35 is supplied with current from the line 38 since it is connected in series therewith through conductors 41, 42 and 37.

In operation when current is first supplied to the series circuit represented by the conductors 38 and 39, the total current of the circuit divides itself between the heater 28 and the shunt circuit through resistor 31. This resistor is adjusted to carry a current equal to the full discharge current. At this arrangement of the circuit, therefore, full operating voltage is applied to the cathode heater 28 and across the discharge path between the electrodes of the lamp. A discharge lamp, however, will not start at normal voltage so that the cathode heater 28 is given time to heat up. In the meantime heater 35 raises the temperature of the thermostatic element and causes the latter to separate the contacts 33 and 34 and thereby break the circuit through resistor 31. The time interval for the breaking of this circuit is so arranged that the heater 28 is brought to the proper temperature. When the circuit is broken the voltage across the lamp is momentarily raised and the lamp is started. The total line

current then divides between the discharge path and the cathode heater. If the lamp does not start within a short predetermined time for some reason a film contact 43 connected between conductors 44 and 45 breaks down and short circuits the winding section 6.

What I claim as new and desire to secure by Letters Patent of the United States, is:

1. In combination, an electric discharge device provided with an anode, a cathode, a heater for said cathode, a constant current circuit, means for dividing the available energy received from said circuit between said cathode heater and the discharge path between said anode and cathode, and a circuit connected in shunt to said electrodes arranged to carry the normal discharge current until the said cathode has been preheated.

2. In combination with an electric discharge lamp provided with a thermionic cathode and an anode, a transformer having a primary winding provided with substantially constant current, a secondary winding having sections connected across said cathode and said electrodes respectively, a load circuit in shunt to the discharge path between said electrodes for shunting the normal load current past said discharge path, and a time delay switch for opening said shunt circuit about said discharge path a predetermined time interval subsequent to the energization of the primary winding.

3. In combination, an electric discharge lamp provided with an anode, a cathode, a heater for said cathode and a discharge path between said anode and cathode, a constant current circuit connected to supply current to said discharge path and heater in multiple, and a shunt circuit arranged to carry the current of said discharge path until the cathode has been preheated.

4. In combination, an electric discharge device provided with an anode and a thermionic cathode provided with a heating circuit, a constant current circuit, means for dividing the available energy received from said circuit between said cathode heating circuit and the discharge path between said anode and cathode, and a circuit connected in shunt to said electrodes arranged to carry the normal discharge current until the said cathode has been preheated.

WILLEM F. WESTENDORP.
